Edward Gottsch

UNITED STATES PATENT OFFICE

JACOB STARR, OF BRONX, NEW YORK, ASSIGNOR OF ONE-HALF TO JULIUS MARGOLIN, OF NEW YORK, N. Y.

ATTACHMENT FOR AUTO-RAISING AND LOWERING AWNINGS AND THE LIKE

Application filed November 20, 1931. Serial No. 576,226.

This invention relates to new and useful improvements in an attachment for automatically releasing and lowering awnings and the like.

The invention has for an object the construction of a device as mentioned above which is of simple, durable construction, dependable in use and efficient in operation, and which can be manufactured and sold at

10 a reasonable cost.

For further comprehension of the invention, and of the objects and advantages thereof, reference will be had to the following description and accompanying drawings, and 15 to the appended claims in which the various novel features of the invention are more particularly set forth.

In the accompanying drawings, forming a material part of this disclosure:—

20 Fig. 1 is a fragmentary elevational view of a window and awning equipped with the attachment.

Fig. 2 is a fragmentary enlarged elevational view looking in the direction of the line 25 2—2 of Fig. 1.

Fig. 3 is a fragmentary enlarged sectional view taken on the line 3—3 of Fig. 2.

Fig. 4 is a sectional view taken on the line 4—4 of Fig. 2.

30 Fig. 5 is a fragmentary enlarged detailed view of one of the telescopic members shown in Fig. 2.

Fig. 6 is a sectional view taken on the line 6—6 of Fig. 2.

35 Fig. 7 is a schematic wiring diagram of the device.

The reference numeral 10 indicates a window frame upon which an awning 11 is mounted. This awning is wound on a roller 40 12 rotatively supported in a pair of standards 13 attached upon the front of the window frame 10. A swingable frame 14 is pivotally mounted at its lower ends 15 upon brackets 16 attached upon the window frame

45 10 and at its upper end is connected with the free end of the awning 11. A means is provided for raising and lowering an awning, and includes an extension portion 17 from the roller 12 extending from the side of the standard 16 and connecting with a gear re-

duction unit 18 in connection with an electric motor 19. A spring stabilizer 20 is arranged upon the shaft portion 17. The stabilizer 20, the gear reduction unit 18, and the motor 19 are shown mounted upon a shelf 21 secured upon a side of the window frame. Details of the stabilizer gear reduction will not be given here since they form no part of the invention.

The electric motor 19 is wired with a reversing switch 22 in an electric circuit 23 which includes a single pole switch 24. The reversing switch 22 controls the direction of rotation of the motor 19. It is equipped with a movable stem 25 adapted to set the switch 60 either in a neutral position or thrown to one side for closing the circuit to rotate the motor in one direction or to the other side for causing rotation of the motor in the other direction.

A pair of arms 26, 27 straddle the stem 25 and are fixed radially on the pivot of the frame 14. These elements are substantially at right angles to each other so that the frame may pivot through 90° to cause one or the other arms to engage against the 65 stem 25.

The mounting of the arms upon the stem is accomplished by an extension portion 28 from the pivot of one of the brackets 16 supporting a disc 29. The arms 26 and 27 are pivotally mounted upon this stem extension and are formed with adjacent serrated faces 30 so that they may engage each other 70

at various angular positons. The hub portion of the arm 26 is provided with pins 31 engaging the side of the disc 29 which is 75 pinned at 32 on the extension 28. A coaxial spring 33 upon the extension 28 acts between one of the hubs of the arms and a lug 34 so as to normally engage the serrations 30 with each other.

The window frame 10 is formed with an opening 35 so that the arms may extend into the frame. A casing 36 mounted on the outside of the frame 10 normally closes this opening.

The arms 26 and 27 are constructed from 95 telescopic sections capable of being locked in various extended positions by set screws 37. A fork 38 also straddles the stem 25 and is pivotally mounted at its rear end 39. Stops

40 limit the pivoting of this fork. The fork 100

is composed of one section 41 extending from the pivot 39 to the tip of one of the arms of the fork and another section 42 constituting the second arm of the fork. This latter section is pivotally mounted upon a stud 43 engaged through the first section. Adjacent faces of the sections are formed with serrations 44 so that the pivoted section 42 may assume any angular position relative to the 5 other section. A coaxial spring 45 is mounted upon the rivet 43 and serves to urge the serrations 44 into engagement with each other. The arms of the fork are composed of telescopic sections capable of being locked 10 in various extended positions by set screws 37. Manual control means is provided for urging the fork 41 one way or the other to move the switch 22 to one or the other of its closed positions. This means comprises a 15 lever 46 pivotally mounted intermediately at 47. One end of this lever is provided with a handle 48 which extends from a panel 49 mounted upon the rear of the window frame. Stops 50 limit pivoting of the lever 46 within 20 certain limits. These limits extend across 25 the pivot 39 of the fork.

An expansion spring 51 is mounted between the inner end of the lever 46 and upon a portion of the fork 41 away from the pivot 39. The arrangement is such that the handle 30 48 may be moved to cause the lever 46 as indicated by the dot and dash lines 52 in which position it will pass the dead center of the 35 spring action 51 upon the fork 41 and cause the fork to pivot to its other position. In Fig. 4, the switch 22 is shown provided with moveable contacts 53 from which the stem 25 projects. These moveable contacts are pivotally supported at 54 and are adapted to be pivoted 40 one way or the other to engage terminals 55 and 56 respectively.

The operation of the device may be traced by assuming it in the condition shown in Fig. 2. In this condition the awning is completely 45 raised and the radial arm 26 is resting against the stem 25 so that the switch 22 is in its neutral position. In this position, the fork 41 is slightly moved away from the stop 40 which is nearest it. To cause the awning 50 to move downwards, it is necessary that the handle 48 be thrown to the position indicated by the dot and dash lines 52. Moving of the handle causes the lever 46 to move to the dot and dash position and the spring 51 will then 55 pivot the fork 41 against the other stop 40 so that one of the arms of the fork strikes the stem 25 and closes the switch 22 to cause the electric motor 19 to rotate to lower the awning 11 when the switch 24 is closed. The degree 60 of lowering may be controlled by closing the switch 24 for a certain length of time. When the awning assumes the completely lowered position the radial arm 27 will have moved up to strike against the stem 25 and 65 move the switch 22 to the neutral position.

In any intermediate position, the direction of raising or lowering of the awning may be changed by merely throwing the handle 48 to cause the fork 41 to close the switch in the opposite direction. The radial adjustments 70 of the fork 41 and of the arms 26 and 27 may be utilized to control the operation of the awning. They may be adjusted so that the awning travels through a shorter distance than 90° or a greater distance. More than 75 this, the lengths of the fork 41 and the arms 26 and 27 may be adjusted to compensate for window frame of different thicknesses. 80

While I have illustrated and described my invention with some degree of particularity, I realize that in practice various alterations 85 therein may be made. I therefore reserve the right and privilege of changing the form of the details of construction or otherwise altering the arrangement of the correlated parts 90 without departing from the spirit or the scope of the invention.

Having thus described my invention, what I claim as new, and desire to secure by United States Letters Patent is:—

1. In an awning having a swingably mounted frame and a roller for receiving the awning covering, means for raising and lowering the awning including an electric circuit, a motor connected in the circuit and with said roller, a reversing switch in said circuit and connected with said motor to control the direction of rotation and having a movable stem to set the switch in a neutral position or one position or the other position, a pair of arms straddling said stem and fixed radially on the pivot of said frame and selectively engageable with said stem to move the switch to its neutral position upon complete raising or lowering of said frame respectively, a fork straddling said stem and pivotally mounted, and manually controlled resilient means for urging said fork one way or the other to move said switch to one or the other of its closed 100 positions.

2. In an awning having a swingably mounted frame and a roller for receiving the awning covering, means for raising and lowering the awning including an electric circuit, a motor connected in the circuit and with said roller, a reversing switch in said circuit and connected with said motor to control the direction of rotation and having a movable stem to set the switch in a neutral position or one position or the other position, a pair of arms straddling said stem and fixed radially on the pivot of said frame and selectively engageable with said stem to move the switch to its neutral position upon complete raising or lowering of said frame respectively, a fork straddling said stem and pivotally mounted, and manually controlled resilient means for urging said fork one way or the other to move said switch to one or the other of its closed 110 positions, means being provided 115

for adjusting the fixed relation of said pair of arms.

3. In an awning having a swingably mounted frame and a roller for receiving the awning covering, means for raising and lowering the awning including an electric circuit, a motor connected in the circuit and with said roller, a reversing switch in said circuit and connected with said motor to control the direction of rotation and having a movable stem to set the switch in a neutral position or one position or the other position, a pair of arms straddling said stem and fixed radially on the pivot of said frame and selectively engageable with said stem to move the switch to its neutral position upon complete raising or lowering of said frame respectively, a fork straddling said stem and pivotally mounted, and manually controlled resilient means for urging said fork one way or the other to move said switch to one or the other of its closed positions, means being provided for adjusting the fixed relation of the arms forming said fork.
- 25 4. In an awning having a swingably mounted frame and a roller for receiving the awning covering, means for raising and lowering the awning including an electric circuit, a motor connected in the circuit and with said roller, a reversing switch in said circuit and connected with said motor to control the direction of rotation and having a movable stem to set the switch in a neutral position or one position or the other position, a pair of arms straddling said stem and fixed radially on the pivot of said frame and selectively engageable with said stem to move the switch to its neutral position upon complete raising or lowering of said frame respectively, a fork straddling said stem and pivotally mounted, and manually controlled resilient means for urging said fork one way or the other to move said switch to one or the other of its closed positions, said pair of arms 45 and said fork being adjustable in length.

In testimony whereof I affix my signature.
JACOB STARR.
